UNITED STATES PATENT OFFICE

109,706

DESIGN FOR A SPINNING WHEEL FOR AN AMUSEMENT DEVICE

Edward C. Fain, Wetumpka, Ala.

Application January 28, 1938, Serial No. 74,690

Term of patent 7 years

To all whom it may concern:

Be it known that I, Edward C. Fain, a citizen of the United States, residing at Wetumpka, in the county of Elmore, and State of Alabama, have invented a new, original, and ornamental Design for Spinning Wheels for Amusement Devices, of which the following is a specification, reference being had to the accompanying drawing, forming part thereof.

Figure 1 is a perspective view of a spinning wheel for an amusement device embodying my new design.

Figure 2 is a central cross-sectional view through the same.

I claim:

The ornamental design for a spinning wheel for an amusement device, as shown.

EDWARD C. FAIN.
